UNITED STATES PATENT OFFICE.

HERBERT SMITH, OF YONKERS, NEW YORK.

SELF-ADJUSTABLE HAT-RETAINER.

1,072,266.

Specification of Letters Patent. Patented Sept. 2, 1913.

Application filed April 26, 1913. Serial No. 763,808.

To all whom it may concern:

Be it known that I, HERBERT SMITH, a citizen of the United States, and a resident of Yonkers, in the county of Westchester and 5 State of New York, have invented a new and Improved Self-Adjustable Hat-Retainer, of which the following is a full, clear, and exact description.

This invention relates to improvements in 10 hat racks and more particularly to a self-adjustable hat retainer for portable hat racks such as are used in hat shops during the process of manufacturing for the purpose of supporting the hats and transporting 15 the same from place to place.

The essential object of the invention is comprehended in the provision of an improved retaining means for the hats designed by application to the racks to hold 20 the hats in upright or inverted positions and designed to adjust itself automatically to hats of different sizes and shapes or styles.

With the above and other objects in view, the invention resides more particularly in 25 the peculiar combination and arrangement of parts which will be illustrated as a preferred embodiment in the accompanying drawings and described in the specification.

Reference is to be had to the accompanying 30 drawings forming a part of this specification, in which similar characters of reference indicate corresponding parts in all the views and in which—

Figure 1 is a front elevation of a hat rack 35 provided with my improved adjustable retainer; Fig. 2 is a vertical sectional view of the device with a hat in position therein and with the retainer shown in solid lines in its operative position and in dotted lines in its 40 inoperative position; Fig. 3 is a fragmentary vertical sectional view of a slightly modified form for holding the hats in an upright position; Fig. 4 is a front elevation of the structure shown in Fig. 3; and Fig. 5 is an 45 enlarged sectional view showing the stop and guide for the connecting rod of the retaining members.

In the drawings, a well known form of hat rack is illustrated, the same embodying 50 spaced rectangular frames 10 and 11 connected at their ends by cross braces 12 and having their top and bottom portions connected at equi-distantly spaced points by means of uprights 13. The bottom portions 55 of the frames 10 are connected by transverse base-boards 14, in which the bottom

portions of the frames are seated, while the extremities of said baseboards extend beyond the frames to support the latter and prevent the same from tipping over. It 60 will also be observed that the frames converge toward their upper ends, and this is for the purpose of efficiently stabilizing the rack while the upper portions of the frames are connected by transverse cleats 15 to further 65 rigidify the structure and to permit the rack to withstand the rough usage to which it is subjected during the transportation of the hats.

The end portions of the frames 10 and the 70 uprights 13 are connected by longitudinal rungs or rods 16 which are disposed in spaced pairs at the rear side of the rack, while the rungs or rods 17 connect said end portions and uprights at the front side of 75 the rack in staggered relation to the rungs or rods 16, as shown in Fig. 2 of the drawings, or as shown in Fig. 3, the rungs 18 are disposed so that the lower rung in each pair will be substantially in alignment horizontally with the rungs 19 at the front of the rack. The purpose of this is to hold the hats in different positions, either inverted or upright, as illustrated, but owing to the rough usage to which the racks are subjected the 80 hats become dislodged easily, resulting in their becoming mixed up and often injured.

It is the object of this invention to prevent the dislodgment of the hats by means of 85 a simple, durable and positively acting contrivance, and with this end in view, for holding the hats in inverted positions the end portions of the frame 10 and the uprights 13 of said frame have journaled thereon in bearing straps 20, preferably adjacent to the rungs 17 and slightly spaced above the same, the crank portions 21 of a plurality of retaining members having substantially semi-circular engaging members between the crank portions and the vertical 90 members of the frame. The extremities of the wire or metal sections forming the retaining members are mounted in similar bearing straps at the ends of the frames and the engaging portions 22 are held centralized 95 with respect to the vertical members of the frame. The racks are so constructed as to hold a predetermined number of hats, but this depends upon the sizes of the hats to be held within reasonable range and the sizes 100 of the racks which may be varied as desired.

In order to hold the retaining members

against longitudinal shifting and to permit them to simultaneously swing on their pivots, each is formed adjacent the ends of the frame with crank levers 23 and 24, the same being connected by rods 25 and 26 so as to connect the same and cause them to be simultaneously swung on their pivots when moved to the inoperative positions shown in dotted lines in the drawings. The connecting rod 25 as well as the connecting rod 26 loosely receive the crank levers through openings therein, and the rod 26 terminates adjacent the upper and lower crank portions of the retaining members corresponding thereto. The upper extremity of the rod 25 is directed rearwardly to provide a substantially horizontally disposed but slightly inclined portion 27, to the inner extremity of which a contractile spring 28 is connected and in turn connected or anchored to the rear frame 11 for raising the rod 25 and moving it toward the front rungs, thus similarly shifting the rod 26 and causing the engaging portions 22 of the retaining members to move to operative positions. In order to guide the rods during this movement a depending stop arm 29 is secured to the adjacent end member of the frame 10, and is provided with an offset lower portion which receives the portion 27 therebeneath and which passes under an inward extension 30 of the rod 25 at a spaced distance below the portion 27 so as to guide the retainers and prevent the rod 25 from being shifted longitudinally with respect to the rack. The spring 28 normally holds the retainers in operative position but they may be lowered through the instrumentality of the rods 25 and 26 by means of a grasping portion 31 bent in an angular direction outwardly at the lower end of the rod 25, and which is designed for engagement beneath a pin or lug 32 extending outwardly from the adjacent end member of the rack for holding the retaining members in the inoperative or dotted line position. It will be observed that as the retaining members are swung outwardly the rod 25 will be spaced from the rack so that its engaging end 31 will pass over the pin 32 to such an extent as to be readily snapped or engaged therebeneath to hold the retaining members against movement under the tension of the spring.

In Fig. 2 of the drawings a hat 33 is shown having a guard band 34 mounted on its crown in contact with the brim of the hat, and in this form of the invention the hats are supported in inverted position so that the brims will extend between the rear pairs of rungs 16, and the hats will be supported by means of the band upon the rungs 17, while the retaining members, through the instrumentality of their engaging members 22, will conform to the curvature of the crowns or bands under the action of the

spring 28 tending to elevate the same. Thus it will be obvious that the rungs 16 will prevent rearward displacement of the hats while the retaining members will prevent forward displacement of the hats or dislodgment of the same from the rack. 70

In the form of the invention shown in Figs. 3 and 4 of the drawings, the crank portions of the retaining members are spaced above the rungs 19 to provide spaces 35 for accommodating the brim of the hat, so that the hats will be supported substantially horizontally, as shown, and in upright positions. In this manner of supporting the hats the retaining members will act in the usual way under the tension of the spring 28, but the retaining members are completely elevated when the hats are placed in position, then the said members are lowered to the solid line position shown in Fig. 3 so that when they are released the spring will draw the engaging members 22 against the guard bands 34 and displacement of the hats will be prevented. 80

Considerable advantage attaches to the device owing to the fact that the retaining members may be held in horizontal positions and in this manner act as supports for the hats, but in addition to this the retaining members are simultaneously actuated, and after the rack has been stacked with hats it may be transported with safety and the retaining members then moved to inoperative positions, whereby the hats may be removed without obstruction. 100

Having thus described my invention, what I claim as new and desire to secure by Letters Patent is: 100

1. The combination of a hat rack embodying spaced frames, spaced pairs of rungs carried by one frame and coöperating rungs carried by the other frame for supporting the hats with the brims engaged between the pairs of rungs and the crowns supported on the other rungs, retaining sections extending longitudinally across the rack and having engaging portions and intermediate portions journaled on the frame having the coöperating rungs, crank portions formed with said retaining sections, rods connecting said crank portions, one of said rods having a grasping portion for shifting the retaining sections on their pivots, and means for guiding the rod having the grasping portion. 110

2. The combination of a hat rack embodying spaced frames, spaced pairs of rungs carried by one frame and coöperating rungs carried by the other frame for supporting the hats with the brims engaged between the pairs of rungs and the crowns supported on the other rungs, retaining sections extending longitudinally across the rack and having engaging portions and intermediate portions journaled on the frame having the co- 130

operating rungs, crank portions formed with said retaining sections, rods connecting said crank portions, one of said rods having a grasping portion for shifting the retaining sections on their pivots, said rod having the grasping portion being provided with an inwardly extended end, a spring connecting the frame to said end for exerting pull on the latter to move the retaining sections to engaging positions, and means carried by the frame and engaging said in-turned end for guiding the rods during their movement.

3. The combination of a hat rack embodying spaced frames, spaced pairs of rungs carried by one frame and coöperating rungs carried by the other frame for supporting the hats with the brims engaged between the pairs of rungs and the crowns supported on the other rungs, retaining sections extending longitudinally across the rack and having engaging portions and intermediate por-

tions journaled on the frame having the co-operating rungs, crank portions formed with said retaining sections, rods connecting 25 said crank portions, one of said rods having a grasping portion for shifting the retaining sections on their pivots, said rod having the grasping portion being provided with an inwardly extended end, a spring 30 connecting the frame to said end for exerting pull on the latter to move the retaining sections to engaging positions, and means carried by the frame and engaging said in-turned end for guiding the rods during 35 their movements, said means also forming a stop.

In testimony whereof I have signed my name to this specification in the presence of two subscribing witnesses.

HERBERT SMITH.
